(57) **CLAIM**

The ornamental design for a stepping exercise device, as shown and described.

DESCRIPTION

FIG. 1 is a perspective view of the stepping exercise device; FIG. 2 is a front elevation view of the stepping exercise device;

FIG. 3 is a rear elevation view of the stepping exercise device;

FIG. 4 is a left side elevational view of the stepping exercise device;

FIG. 5 is a right side elevational view of the stepping exercise device;

FIG. 6 is a top plan view of the stepping exercise device; and,

FIG. 7 is a bottom plan view of the stepping exercise device. Any broken lines shown in FIGS. 1-7 are included for the purpose of illustrating portions of the stepping exercise device that form no part of the claimed design.

1 Claim, 7 Drawing Sheets
